(57) **ABSTRACT**

Provided is a display device capable of expanding a color space without causing an increase in IC size and cost. A signal processing circuit (100) is provided with: a signal separation unit (110) configured to separate an input video signal into components of individual colors; an expanded video signal generation unit (130) configured to perform an expansion process for increasing a signal value of the input video signal, and output data obtained by the expansion process as an expanded video signal; an expansion coefficient decision unit (120) configured to decide an expansion coefficient E to be used for the expansion process; and an output video signal generation unit (140) configured to generate an output video signal to be outputted to the display panel based on the expanded video signal. The expansion coefficient decision unit (120) decides an inverse of saturation, obtained based on the input video signal, as the expansion coefficient E for each pixel.

DISPLAY DEVICE AND METHOD FOR EXPANDING COLOR SPACE

TECHNICAL FIELD

The present invention relates to a display device, and more specifically relates to a display device that expands a color space by displaying white in addition to the three primary colors.

BACKGROUND ART

Generally, in a liquid crystal display device for producing a color display, one pixel is divided into three sub pixels: a red sub pixel provided with a color filter that transmits red light, a green sub pixel provided with a color filter that transmits green light, and a blue sub pixel provided with a color filter that transmits blue light. The color display can be produced by the color filters provided in these three sub pixels. However, in recent years, for the purpose of expanding a color space (a color gamut or a color reproduction range), there has also been developed a liquid crystal display device in which one pixel includes a white sub pixel that transmits white light, and the above three sub pixels (i.e., a liquid crystal display device in which one pixel includes the white sub pixel, the red sub pixel, the green sub pixel, and the blue sub pixel).

Further, since the liquid crystal display device employing a color filter system as described above has the problem of having low light use efficiency, a liquid crystal display device employing a field-sequential color system in which a color display is produced without using color filters has also become widespread. In a typical liquid crystal display device adopting the field-sequential color system, one frame period being a display period for one screen is temporally divided into three fields. While the field is also referred to as a subframe, in the following description, the term "field" is used uniformly.

In the liquid crystal display device employing the field-sequential color system, typically, one frame period is temporally divided into a field (red field) for displaying a red screen based on a red component of an input video signal, a field (green field) for displaying a green screen based on a green component of an input video signal, and a field (blue field) for displaying a blue screen based on a blue component of an input video signal. By displaying the primary colors one by one as above, a color image is displayed on a liquid crystal panel. Displaying a color image in such a manner eliminates the need for color filters in the liquid crystal display device employing the field-sequential color system. Accordingly, the liquid crystal display device employing the field-sequential color system has high light use efficiency as compared with that of the liquid crystal display device employing the color filter system. Hence, the liquid crystal display device employing the field-sequential color system is suitable for increasing luminance and reducing power consumption.

In the liquid crystal display device employing the field-sequential color system described above, a field (white field) for displaying a white screen is provided in addition to the above three fields in order mainly to reduce color breakup.

As described above, in the liquid crystal display device employing the color filter system, the white sub pixel is provided so as to expand the color space, while in the liquid crystal display device employing the field-sequential color system, the white field is provided so as mainly to reduce color breakup. Meanwhile, a signal value for white is

decided based on a signal value for red, a signal value for green, and a signal value for blue. At that time, an expansion process for increasing signal values for red, green and blue is performed so as to expand the color space. Generally, the expansion process is performed by multiplying an original signal value for each of red, green, and blue by a constant coefficient (hereinafter referred to as an "expansion coefficient").

Japanese Patent Application Laid-Open No. 2010-33009, for example, discloses an invention of an image display device in which one pixel is configured by four sub pixels (a red sub pixel, a green sub pixel, a blue sub pixel, and a white sub pixel) to expand a color space. In the image display device disclosed in Japanese Patent Application Laid-Open No. 2010-33009, "the maximum value of lightness (the maximum lightness)" with saturation taken as a variable is previously stored into a signal processing unit, and an expansion coefficient is decided based on saturation obtained from an input video signal and the maximum lightness stored in the signal processing unit. The expansion coefficient is then used to perform the expansion process on the input video signal. In such a manner, the color space (HSV color space) is expanded from one as shown in FIG. 11 to one as shown in FIG. 12.

[Patent Document 1] Japanese Patent Application Laid-Open No. 2010-33009

SUMMARY OF THE INVENTION

Problems to be Solved by the Invention

However, according to the image display device disclosed in Japanese Patent Application Laid-Open No. 2010-33009, the maximum lightness needs to be previously stored into the signal processing unit. That is, a memory or the like for storing the maximum lightness is required. This has caused increases in IC size and cost.

Accordingly, an object of the present invention is to achieve a display device capable of expanding a color space without causing increases in IC size and cost.

Means for Solving the Problem

50 A first aspect of the present invention is directed to a display device provided with a display panel for displaying an image, the display device including:

an expanded video signal generation unit configured to perform an expansion process for increasing a signal value of an input video signal, and output data obtained by the expansion process as an expanded video signal;

an expansion coefficient decision unit configured to decide an expansion coefficient to be used for the expansion process by the expanded video signal generation unit; and

an output video signal generation unit configured to generate an output video signal to be outputted to the display panel based on the expanded video signal, wherein

the expansion coefficient decision unit decides an inverse of saturation, obtained based on the input video signal, as an expansion coefficient for each pixel, and

the expanded video signal generation unit multiplies the expansion coefficient, decided by the expansion coefficient

decision unit, by a signal value of the input video signal for each pixel, to generate the expanded video signal.

According to a second aspect of the present invention, in the first aspect of the present invention,

when a pixel to be processed for obtaining the expansion coefficient is defined as a target pixel, the expansion coefficient decision unit decides an expansion coefficient to be used for the expansion process on an input video signal of the target pixel based on input video signals of a plurality of pixels including the target pixel and pixels around the target pixel.

According to a third aspect of the present invention, in the second aspect of the present invention,

the expansion coefficient decision unit decides an average of inverses of saturation, obtained based on input video signals of the plurality of pixels, as an expansion coefficient to be used for the expansion process on an input video signal of the target pixel.

According to a fourth aspect of the present invention, in the second aspect of the present invention,

the expansion coefficient decision unit decides a median of inverses of saturation, obtained based on input video signals of the plurality of pixels, as an expansion coefficient to be used for the expansion process on an input video signal of the target pixel.

According to a fifth aspect of the present invention, in the first aspect of the present invention,

the input video signal includes a red input video signal, a green input video signal, and a blue input video signal,

the display panel is configured to display an image based on the output video signal including a white output video signal, a red output video signal, a green output video signal, and a blue output video signal,

the expanded video signal generation unit:

generates a red expanded video signal based on the red input video signal;

generates a green expanded video signal based on the green input video signal; and

generates a blue expanded video signal based on the blue input video signal,

the output video signal generation unit:

generates the white output video signal based on the red expanded video signal, the green expanded video signal, and the blue expanded video signal;

generates the red output video signal based on the white output video signal and the red expanded video signal;

generates the green output video signal based on the white output video signal and the green expanded video signal; and

generates the blue output video signal based on the white output video signal and the blue expanded video signal.

According to a sixth aspect of the present invention, in the fifth aspect of the present invention,

one pixel includes a white sub pixel that displays white, a red sub pixel that displays red, a green sub pixel that displays green, and a blue sub pixel that displays blue,

the white output video signal is provided to the white sub pixel,

the red output video signal is provided to the red sub pixel, the green output video signal is provided to the green sub pixel, and

the blue output video signal is provided to the blue sub pixel.

According to a seventh aspect of the present invention, in the fifth aspect of the present invention,

the display panel is driven by a field-sequential color system in which one frame period is divided into a plurality of fields and a screen is rewritten in each of the fields to produce a color display

one frame period includes a white field for displaying a white screen, a red field for displaying a red screen, a green field for displaying a green screen, and a blue field for displaying a blue screen,

the white output video signal is outputted to the display panel in the white field,

the red output video signal is outputted to the display panel in the red field,

the green output video signal is outputted to the display panel in the green field, and

the blue output video signal is outputted to the display panel in the blue field.

An eighth aspect of the present invention is directed to a method for expanding a color space in a display device provided with a display panel for displaying an image, the method including:

an expanded video signal generation step of performing an expansion process for increasing a signal value of an input video signal, and outputting data obtained by the expansion process as an expanded video signal;

an expansion coefficient decision step of deciding an expansion coefficient that is used for the expansion process in the expanded video signal generation step; and

an output video signal generation step of generating an output video signal to be outputted to the display panel based on the expanded video signal, wherein

in the expansion coefficient decision step, an inverse of saturation, obtained based on the input video signal, is decided as an expansion coefficient for each pixel, and

in the expanded video signal generation step, the expansion coefficient decided in the expansion coefficient decision step is multiplied by a signal value of the input video signal for each pixel, to generate the expanded video signal.

Effects of the Invention

According to the first aspect of the present invention, in the display device where the expansion process is performed, an inverse of saturation, obtained based on the input video signal, is decided as an expansion coefficient to be used for the expansion process. Since simply the inverse of the saturation is decided as the expansion coefficient as thus described, there is no need for a constituent that holds an expansion coefficient corresponding to each saturation, differently from the prior art. It is thus possible to perform the expansion process on the input video signal without providing the constituent for holding an expansion coefficient corresponding to each saturation. From the above, there is achieved a display device capable of expanding a color space without causing increases in IC size and cost.

According to the second aspect of the present invention, the expansion coefficient to be used for the expansion process on an input video signal of a certain pixel is decided based on input video signals of a plurality of pixels including the certain pixel and pixels around the pixel. This prevents

a great change in the expansion coefficient value between adjacent pixels. Accordingly, an image with smooth color variation is displayed. From the above, there is achieved a display device capable of expanding a color space without causing increases in IC size and cost, and also capable of obtaining a display image with smooth color variation.

According to the third aspect of the present invention, similarly to the second aspect of the present invention, there

is achieved a display device capable of expanding a color space without causing increases in IC size and cost, and also capable of obtaining a display image with smooth color variation.

According to the fourth aspect of the present invention, similarly to the second aspect of the present invention, there is achieved a display device capable of expanding a color space without causing increases in IC size and cost, and also capable of obtaining a display image with smooth color variation.

According to the fifth aspect of the present invention, since a white display is produced, there is achieved a display device capable of effectively expanding a color space without causing increases in IC size and cost.

According to the sixth aspect of the present invention, there is achieved a display device employing a color filter system and capable of expanding a color space without causing increases in IC size and cost.

According to the seventh aspect of the present invention, a field-sequential color system is adopted for the driving system of the display panel. By using the field-sequential color system, color filters are not required, thereby making the light use efficiency high as compared with that of the display device employing the color filter system. This enables an increase in luminance and reduction in power consumption. From the above, there is achieved a display device capable of expanding a color space without causing increases in IC size and cost, and also capable of increasing luminance and reducing power consumption.

According to the eighth aspect of the present invention, the same effect as that of the first aspect of the present invention can be exerted in the method for expanding a color space in the display device.

BRIEF DESCRIPTION OF THE DRAWINGS

FIG. 1 is a block diagram showing a configuration of a signal processing circuit in a liquid crystal display device according to a first embodiment of the present invention.

FIG. 2 is a block diagram showing an overall configuration of the liquid crystal display device in the first embodiment.

FIG. 3 is a schematic diagram showing a configuration of one pixel in the first embodiment.

FIG. 4 is a diagram for describing data conversion by a white separation process in the first embodiment.

FIG. 5 is a diagram for describing three psychological attributes of color.

FIG. 6 is a diagram for describing hue.

FIG. 7 is a diagram for describing hue.

FIG. 8 is a diagram for describing the effect in the first embodiment.

FIG. 9 is a diagram for describing a method of obtaining an expansion coefficient in a liquid crystal display device according to a second embodiment of the present invention.

FIG. 10 is a diagram showing a configuration of one frame period in a liquid crystal display device according to a third embodiment of the present invention.

FIG. 11 is a schematic view showing a normal HSV color space.

FIG. 12 is a schematic view showing an expanded HSV color space.

MODES FOR CARRYING OUT THE INVENTION

Embodiments of the present invention be described below with reference to the accompanying drawings. Note that

signal values of an input video signal and some other signal are assumed to be not smaller than 0 and not larger than 1.

1. First Embodiment

<1.1 Overall Configuration and Operation Overview>

FIG. 2 is a block diagram showing an overall configuration of a liquid crystal display device according to a first embodiment of the present invention. This liquid crystal display device includes a signal processing circuit 100, a timing controller 200, a gate driver 310, a source driver 320, an LED driver 330, a liquid crystal panel 400, and a backlight 500. The gate driver 310 or the source driver 320, or both of those drivers, may be provided in the liquid crystal panel 400. The liquid crystal panel 400 includes a display unit 410 for displaying an image. In the present embodiment, it is assumed that the backlight 500 is configured by a red LED, a green LED, and a blue LED.

As for FIG. 2, a plurality of (n) source bus lines (video signal lines) SL1 to SLn and a plurality of (m) gate bus lines (scanning signal lines) GL1 to GLm are disposed in the display unit 410. A pixel formation portion 4 which forms a pixel (sub pixel) provided at a corresponding intersection of the source bus lines SL1 to SLn and the gate bus lines GL1 to GLm. That is, the display unit 410 includes a plurality of (nxm) pixel formation portions 4. The plurality of pixel formation portions 4 are arranged in a matrix form and thereby form a pixel matrix of m rowsxn columns. Each pixel formation portion 4 includes a thin-film transistor (TFT) 40 which is a switching element having a gate terminal connected to a gate bus line GL passing through a corresponding intersection, and a source terminal connected to a source bus line SL passing through the intersection; a pixel electrode 41 connected to a drain terminal of the TFT 40; a common electrode 44 and an auxiliary capacitance electrode 45 which are provided so as to be shared by the plurality of pixel formation portions 4; a liquid crystal capacitance 42 formed of the pixel electrode 41 and the common electrode 44; and an auxiliary capacitance 43 formed of the pixel electrode 41 and the auxiliary capacitance electrode 45. A pixel capacitance 46 is composed of the liquid crystal capacitance 42 and the auxiliary capacitance 43. Note that only those components provided in one pixel formation portion 4 are shown in the display unit 410 in FIG. 2.

Meanwhile, as the TFTs 40 in the display unit 410, for example, an oxide TFT (a thin-film transistor using an oxide semiconductor as a channel layer) can be adopted. More specifically, a TFT whose channel layer is formed of indium-gallium-zinc-oxide (In—Ga—Zn—O) that is an oxide semiconductor containing indium (In), gallium (Ga), zinc (Zn), and oxygen (O) as the main components (such a TFT is hereinafter referred to as “In—Ga—Zn—O-TFT”) can be adopted as the TFT 40. By adopting such an In—Ga—Zn—O-TFT, the effects of an improvement in definition and a reduction in power consumption can be obtained, and in addition, the writing speed can be increased over conventional cases. Moreover, it is also possible to adopt a transistor using, as a channel layer, an oxide semiconductor other than indium-gallium-zinc-oxide (In—Ga—Zn—O). The same effects are obtained also when a transistor using an oxide semiconductor containing, for example, at least one of indium, gallium, zinc, copper (Cu), silicon (Si), tin (Sn), aluminum (Al), calcium (Ca), germanium (Ge), and lead (Pb) as the channel layer is adopted. Note that the present invention does not intend to exclude the use of other TFTs than oxide TFTs.

FIG. 3 is a schematic diagram showing a configuration of one pixel in the present embodiment. As illustrated in FIG. 3, in the present embodiment, one pixel 60 includes a white sub pixel 60(W) for displaying white, a red sub pixel 60(R) for displaying red, a green sub pixel 60(G) for displaying green, and a blue sub pixel 60(B) for displaying blue. Each of these sub pixels of the respective colors correspond to one pixel formation portion 4 described above. As thus described, the liquid crystal display device according to the present embodiment is a liquid crystal display device employing a color filter system. Note that the configuration shown in FIG. 3 is an example, and the present invention is not limited thereto. The present invention is also applicable to a case where a configuration other than the configuration shown in FIG. 3 is adopted.

Next, operation of the constituents shown in FIG. 2 will be described. The signal processing circuit 100 receives an input video signal DIN, and performs an expansion process for expanding a color space, or some other process. The signal processing circuit 100 then outputs a white output video signal Wo, a red output video signal Ro, a green output video signal Go, and a blue output video signal Bo, to be provided to the liquid crystal panel 400.

The timing controller 200 receives the white output video signal Wo, the red output video signal Ro, the green output video signal Go, and the blue output video signal Bo, and outputs a digital video signal DV including those output video signals of the four colors, a gate start pulse signal GSP and a gate clock signal GCK which are for controlling operation of the gate driver 310, a source start pulse signal SSP, source clock signal SCK, and a latch strobe signal LS which are for controlling operation of the source driver 320, and an LED driver control signal S1 for controlling operation of the LED driver 330.

The gate driver 310 repeats the application of an active scanning signal to each gate bus line GL with one vertical scanning period as a cycle, based on the gate start pulse signal GSP and gate clock signal GCK which are transmitted from the timing controller 200.

The source driver 320 receives the digital video signals DV, source start pulse signal SSP, source clock signal SCK, and latch strobe signal LS which are transmitted from the timing controller 200, and applies a driving video signal to each source bus line SL. At this time, the source driver 320 sequentially holds a digital video signal DV indicating a voltage to be applied to each source bus line SL, at timing at which a pulse of the source clock signal SCK occurs. Then, the held digital video signals DV are converted into analog voltages at timing at which a pulse of the latch strobe signal LS occurs. The converted analog voltages are simultaneously applied to all source bus lines SL1 to SLn, as driving video signals.

The LED driver 330 outputs a light source control signal S2 for controlling luminance of each LED that constitutes the backlight 500, based on the LED driver control signal S1 transmitted from the timing controller 200. The backlight 500 controls the luminance of each LED based on the light source control signal S2.

As described above, the scanning signals are applied to the gate bus lines GL1 to GLn, the driving video signals are applied to the source bus lines SL1 to SLn, and the luminance of each LED is controlled, by which an image corresponding to the input video signal DIN is displayed on the display unit 410 of the liquid crystal panel 400.

<1.2 Signal Processing Circuit>

Next, the configuration and operation of the signal processing circuit 100 will be described in detail. FIG. 1 is a

block diagram showing the configuration of the signal processing circuit 100 according to the present embodiment. The signal processing circuit 100 includes a signal separation unit 110, an expansion coefficient decision unit 120, an expanded video signal generation unit 130, and an output video signal generation unit 140.

The signal separation unit 110 separates the input video signal DIN transmitted from the outside into a red input video signal Ri being a red component, a green input video signal Gi being a green component, a blue input video signal Bi being a blue component. The expansion coefficient decision unit 120 obtains, for each pixel, an expansion coefficient E to be used for the expansion process based on the red input video signal Ri, the green input video signal Gi, and the blue input video signal Bi. A method of obtaining this expansion coefficient E will be described in detail later. The expanded video signal generation unit 130 multiplies each of the red input video signal Ri, the green input video signal Gi, and the blue input video signal Bi by the expansion coefficient E, to generate a red expanded video signal Re, a green expanded video signal Ge, and a blue expanded video signal Be. The output video signal generation unit 140 performs a process (hereinafter referred to as a "white separation process") for separating white data from the RGB data including the red expanded video signal Re, the green expanded video signal Ge, and the blue expanded video signal Be, to generate the white output video signal Wo, the red output video signal Ro, the green output video signal Go, and the blue output video signal Bo which are to be outputted to the liquid crystal panel 400.

Specific examples of conversion of data by the white separation process will be described here. A first example and a second example will be described as specific examples, but the present invention is not limited thereto. For example, components for the respective colors (signal values of the expanded video signals for the respective colors) before the conversion are assumed to be like those denoted by reference character 80 in FIG. 4. Among the red component (R), the green component (G), and the blue component (B), the red component is the minimum component.

In such a case, in the first example, the size of the white component (W) is set to be the same as the size of the red component before the conversion. The size of the green component after the conversion is set to be a size shown by an arrow of reference character 81 in FIG. 4, and the size of the blue component after the conversion is set to be a size shown by an arrow of reference character 82 in FIG. 4. It should be noted that, at this time, the size of the red component after the conversion is set to be zero. As a result, the components for the respective colors after the conversion are as those shown by reference character 83 in FIG. 4. As described above, when the size of the red component, the size of the green component, and the size of the blue component before the white separation process are respectively represented by R1, G1, and B1, and the size of the white component, the size of the red component, the size of the green component, and the size of the blue component after white separation process are respectively represented by W2, R2, G2, and B2, W2, R2, G2, and B2 are respectively obtained by the following formulas (1), (2), (3), and (4):

$$W2 = \min(R1, G1, B1) \quad (1)$$

$$R2 = R1 - W2 \quad (2)$$

$$G2 = G1 - W2 \quad (3)$$

$$B2 = B1 - W2 \quad (4)$$

where $\min(R1, G1, B1)$ is a function representing the minimum value among R1, G1, and B1.

In the second example, the size of the white component (W) is set to be a size obtained by multiplying the size of the red component before the conversion by a predetermined coefficient C. That is, a size W2 of the white component after the white separation process is obtained by the following formula (5):

$$W2 = C \times \min(R1, G1, B1) \quad (5)$$

Based on W2 obtained as above, similarly to the first example, the size of the red component, the size of the green component and the size of the blue component after the white separation process are obtained.

<1.3 Expansion Process>

As described above, in order to expand the color space, the expansion process is performed in which the signal value of the input video signal is multiplied by the expansion coefficient E which is a constant coefficient. Meanwhile, a variety of color spaces have hitherto been considered for performing a variety of processes concerning colors. In the present embodiment, the expansion process is performed using an HSV color space. The HSV color space is a color space made up of three components of "hue", "saturation", and "lightness." These hue, saturation and lightness are called three psychological attributes of color. The hue is a color shade such as "red . . . yellow . . . green . . . blue . . . purple." The lightness is the degree of brightness of color. The saturation is the degree of color vividness. These three psychological attributes are generally illustrated as shown in FIG. 5. In FIG. 5, the lightness is shown in a vertical direction, and a vertical line represents an achromatic axis. The higher the position on the achromatic axis the higher the lightness, and the lower the position on the achromatic axis the lower the lightness. Further, the greater the distance from the achromatic axis, the higher the saturation. The hue is represented by a circumference with the achromatic axis at the center. As shown in FIG. 6, colors such as "red . . . yellow . . . green . . . blue . . . purple" are present around the achromatic axis. As described above, the hue represents a color shade, and the saturation represents the color vividness. On the other hand, the lightness merely represents the brightness of color. It is thus considered that an impression a person gets from a displayed image greatly changes when the hue or the saturation changes rather than when the lightness changes. Accordingly, the expansion process is performed as described below to increase only the lightness without changing the hue or the saturation. It should be noted that, in the following, signal values of the red input video signal R1, the green input video and the blue input video signal B1 are simply referred to as R1, G1 and B1. Further, the value of the expansion coefficient E is simply referred to as E.

Concerning the input video signal DIN, the hue H is expressed by the following formula (6) when R1 is the minimum, the hue H is expressed by the following formula (7) when G1 is the minimum, and the hue H is expressed by the following formula (8) when B1 is the minimum. Here, $\max(R1, G1, B1)$ is a function representing the maximum value among R1, G1, and B1, and $\min(R1, G1, B1)$ is a function representing the minimum value among R1, G1, and B1. As shown in FIG. 7, it is assumed that red, green, and blue correspond to 0 degree, 120 degrees, and 240 degrees, respectively.

5

[Formula 1]

$$H = \frac{60 \times (Bi - Gi)}{\max(Ri, Gi, Bi) - \min(Ri, Gi, Bi)} + 180 \quad (6)$$

[Formula 2]

$$H = \frac{60 \times (Ri - Bi)}{\max(Ri, Gi, Bi) - \min(Ri, Gi, Bi)} + 300 \quad (7)$$

[Formula 3]

$$H = \frac{60 \times (Gi - Ri)}{\max(Ri, Gi, Bi) - \min(Ri, Gi, Bi)} + 60 \quad (8)$$

15

Further, concerning the input video signal DIN, the saturation S is expressed by the following formula (9):

[Formula 4]

$$S = \frac{\max(Ri, Gi, Bi) - \min(Ri, Gi, Bi)}{\max(Ri, Gi, Bi)} \quad (9)$$

25

From the above formulas (6) and (9), it is grasped that, even when each of R1, G1, and B1 is multiplied by a constant coefficient, the hue H and the saturation S remain unchanged.

30

Further, concerning the input video signal DIN, the lightness V is expressed by the following formula (10):

$$V = \max(Ri, Gi, Bi) \quad (10)$$

35

Therefore, the lightness Ve obtained by the expansion process in which the signal value of each color contained in the input video signal DIN is multiplied by the expansion coefficient E is expressed by the following formula (11):

$$Ve = E \times \max(Ri, Gi, Bi) \quad (11)$$

40

From the above, the expansion process is performed on the input video signal DIN by using the expansion coefficient E whose value is larger than 1, thereby allowing an increase in only the lightness without changing the hue or the saturation. In the present embodiment, the expanded video signal generation unit 130 performs the expansion process as thus described. The expanded video signal generation unit 130 then outputs data obtained by the expansion process as the expanded video signals (the red expanded video signal Re, the green expanded video signal Ge, and the blue expanded video signal Be).

45

<1.4 Method for Deciding Expansion Coefficient>

50

As described above, by providing the white sub pixel, the HSV color space can be expanded from one as shown in FIG. 11 to one as shown in FIG. 12. The value of the expansion coefficient E for expanding the color space in such a manner is the maximum lightness corresponding to each saturation S based on the input video signal DIN. Therefore, in the image display device disclosed in Japanese Patent Application Laid-Open No. 2010-33009, the maximum lightness with saturation taken as a variable is previously stored into the signal processing unit, and an expansion coefficient is decided based on saturation obtained from an input video signal and the maximum lightness stored in the signal processing unit. In contrast, in the present embodiment, an inverse of saturation obtained from the input video signal DIN is decided as the expansion coefficient E for each pixel. The reason for simply deciding the inverse of the saturation as the expansion coefficient E like this will be described hereinafter.

55

60

65

In general, the signal value for white is obtained based on the expanded video signal (data obtained by performing the expansion process on the input video signal). Typically, the signal value for white (the signal value of the white output video signal W_o) is made equal to the minimum value among the signal value of the red expanded video signal R_e , the signal value of the green expanded video signal G_e , and the signal value of the blue expanded video signal B_e . The signal value of the output video signal for each color is set at a difference between the signal value of the expanded video signal for the relevant color and the signal value of the white output video signal W_o .

Meanwhile, since the liquid crystal cannot be driven by a value exceeding the maximum output value, the signal value of the output video signal needs to be not larger than 1. Hence, the maximum value among the signal value of the red output video signal R_o , the signal value of the green output video signal G_o , and the signal value of the blue output video signal B_o needs to be not larger than 1. In other words, a difference between the maximum value of the expanded video signals (the maximum value among the signal value of the red expanded video signal R_e , the signal value of the green expanded video signal G_e , and the signal value of the blue expanded video signal B_e) and the signal value for white (the signal value of the white output video signal W_o) needs to be not larger than 1 (the maximum output value). Here, as described above, the signal value for white (the signal value of the white output video signal W_o) is made equal to the minimum value among the signal value of the red expanded video signal R_e , the signal value of the green expanded video signal G_e , and the signal value of the blue expanded video signal B_e . Hence, the following formula (12) should be established:

[Formula 5]

$$E \times \max(R_i, G_i, B_i) - E \times \min(R_i, G_i, B_i) \leq 1 \quad (12)$$

From the above formula (12), the following formula (13) should be established concerning the expansion coefficient E :

[Formula 6]

$$E \leq \frac{1}{\max(R_i, G_i, B_i) - \min(R_i, G_i, B_i)} \quad (13)$$

Since the lightness V_e obtained by the expansion process can be expressed by the above formula (11), the expansion coefficient E is expressed by the following formula (14):

[Formula 7]

$$E = \frac{V_e}{\max(R_i, G_i, B_i)} \quad (14)$$

When the above formula (14) is substituted for the above formula (13), the following formula (15) is obtained:

[Formula 8]

$$\frac{V_e}{\max(R_i, G_i, B_i)} \leq \frac{1}{\max(R_i, G_i, B_i) - \min(R_i, G_i, B_i)} \quad (15)$$

From the above formula (15), the following formula (16) is obtained concerning the color value V_e :

[Formula 9]

$$V_e \leq \frac{\max(R_i, G_i, B_i)}{\max(R_i, G_i, B_i) - \min(R_i, G_i, B_i)} \quad (16)$$

Thus, "Ve's maximum value (maximum lightness) V_{max} " in a case in which the saturation S is based on the input video signal DIN is expressed by the following formula (17).

[Formula 10]

$$V_{max} = \frac{\max(R_i, G_i, B_i)}{\max(R_i, G_i, B_i) - \min(R_i, G_i, B_i)} \quad (17)$$

Since the saturation S is expressed by the above formula (9), it is grasped that the right side of the above formula (17) is an inverse of the saturation S . Further, as described above, the value of the expansion coefficient E is the maximum lightness corresponding to each saturation S based on the input video signal DIN. Accordingly, above V_{max} is the expansion coefficient E , and its value is the inverse of the saturation S .

From the above, in the present embodiment, the inverse of the saturation obtained from the input video signal DIN is decided as the expansion coefficient E . Then, the expansion process is performed in the expanded video signal generation unit **130** by using the expansion coefficient E . However, the maximum value of the expansion coefficient E is the maximum lightness (($K+1$) in FIG. 12) for the white sub pixel.

<1.5 Effects>

In the prior art, when the expansion process is to be performed on the input video signal in order to expand the color space, the expansion coefficient corresponding to each saturation is previously held, and the expansion coefficient to be used for the expansion process is decided in accordance with saturation obtained from the input video signal. That is, in the prior art, the constituent for holding an expansion coefficient corresponding to each saturation (a maximum lightness storage unit in FIG. 8) has been required. In contrast, according to the present embodiment, in the liquid crystal display device that performs the expansion process on the input video signal in order to expand the color space, the inverse of the saturation obtained based on the input video signal is decided as the expansion coefficient to be used for the expansion process. Hence, in the present embodiment, since it is sufficient for the expansion coefficient decision unit **120** to be able to calculate the inverse of the saturation obtained from the input video signal, the constituent for holding an expansion coefficient corresponding to each saturation is not provided (see FIG. 8), differently from the prior art. Thus, according to the present embodiment, it is possible to perform the expansion process on the input video signal without providing the constituent for holding an expansion coefficient corresponding to each saturation. That is, there is achieved a display device capable of expanding a color space without causing increases in IC size and cost.

<2.1 Overview>

In the above first embodiment, the expansion coefficient E for a certain pixel (hereinafter referred to as a “target pixel”) is decided based only on a value of an input video signal for the target pixel. However, in a case in which the expansion coefficient E is decided in this manner, at the time of the expansion coefficients E being greatly different between adjacent pixels, color variation concerning the display image may not be smooth. Hence, in the present embodiment, the configuration capable of obtaining a display image with smooth color variation is adopted. It should be noted that, since the overall configuration and the configuration of the signal processing circuit 100 are the same as those of the first embodiment described above, the descriptions thereof are omitted (see FIGS. 1 to 3).

<2.2 Method of Obtaining Expansion Coefficient>

In the above first embodiment, the expansion coefficient E for the target pixel is decided based on the signal value of the j put video signal for the target pixel. In contrast, in the present embodiment, the expansion coefficient E for the target pixel is decided based on signal values of input video signals for a plurality of pixels including the target pixel and pixels therearound. Specifically, the expansion coefficient decision unit 120 first obtains “inverses of saturation” based on the signal values of the input video signals for the plurality of pixels including the target pixel and pixels therearound. The expansion coefficient decision unit 120 then decides an average of the “inverses of saturation” for the plurality of pixels, as the expansion coefficient E for the target pixel.

Assuming that a pixel denoted reference character 71 in FIG. 9 is the target pixel, for example, the above average (the average of the inverses of saturation) is calculated by using signal values of input video signals DIN for pixels in a range denoted by reference character 72 in FIG. 9. Note that the average may be calculated by using signal values of input video signals DIN for pixels in a range denoted by reference character 73 in FIG. 9, or the average may be calculated by using signal values of input video signals DIN for pixels in a range other than the above range.

In the present embodiment, the expansion process for expanding the signal value is performed on the input video signal DIN of each pixel by using the expansion coefficient E obtained as described above. Note that a median of the “inverses of saturation” for the plurality of pixels including the target pixel and the pixels therearound may be decided as the expansion coefficient E.

<2.3 Effects>

According to the present embodiment, the value of the expansion coefficient E to be used for the expansion process is decided based on the average of the inverses of saturation for the plurality of pixels. More specifically, when any pixel is taken as the target pixel, the value of the expansion coefficient E to be used for the expansion process on data of the target pixel is decided based on the average of the “inverses of saturation” for the plurality of pixels including the target pixel and the pixels therearound (i.e., based on the input video signals DIN of the plurality of pixels including the target pixel and the pixels therearound). This prevents a great change in expansion coefficient E between adjacent pixels. Accordingly, an image with smooth color variation is displayed. Thus, according to the present embodiment, there is achieved a liquid crystal display device capable of

expanding a color space without causing increases in IC size and cost, and also capable of obtaining a display image with smooth color variation.

<3.1 Configuration, Etc.>

In each of the above first and second embodiments, the description has been given by taking the liquid crystal display device employing the color filter system as an example. However, the present invention is not limited thereto. So, an example where a liquid crystal display device employing a field-sequential color system is adopted will be described as a third embodiment of the present invention.

10 FIG. 10 is a diagram showing a configuration of one frame period in the present embodiment. As shown in FIG. 10, one frame period is temporally divided into a white field for displaying a white screen, a red field for displaying a red screen, a green field for displaying a green screen, and a blue field for displaying a blue screen. In the white field, the red LED, the green LED, and the blue LED come into a lighting state after the lapse of a predetermined period from a field starting point. In the red field, the red LED comes into the lighting state after the lapse of the predetermined period from the field starting point. In the green field, the green LED comes into the lighting state after the lapse of the predetermined period from the field starting point. In the blue field, the blue LED comes into the lighting state after the lapse of the predetermined period from the field starting point. During operation of the liquid crystal display device, the white field, the red field, the green field, and the blue field are repeated. Thereby, the white screen, the red screen, the green screen, and the blue screen are repeatedly displayed, and a desired color image is displayed on the display unit 410. Note that the order of the fields is not particularly limited. The order of the fields may be, for example, the order of “the white field, the blue field, the green field, and the red field.” Further, the length of the period in which the LED is in the lighting state in each field may be set considering response characteristics of the liquid crystal. Moreover, the present invention is also applicable to a case where one frame period is configured by a combination other than the combination of “the white field, the blue field, the green field, and the red field.”

15 The overall configuration is the same as that of the above first embodiment. However, differently from the above first embodiment, each pixel is not divided into a plurality of sub pixels. The signal processing circuit 100 is also the same as that of the above first embodiment. However, as a counter-measure against a slow response speed of the liquid crystal, the signal values of the output video signals (the white output video signal Wo, the red output video signal Ro, the green output video signal Go, and the blue output video signal Bo) may be corrected so that overdriving is performed. Note that the overdriving is a driving system which the liquid crystal panel is supplied with a driving voltage higher than a previously decided gradation voltage corresponding to the signal value in the current field or a driving voltage lower than a previously decided gradation voltage corresponding to the signal value in the current field, in accordance with a combination of a signal value in one previous field and a signal value in the current field. That is, by the overdriving, a correction is made to emphasize a temporal change (not a spatial change) of the signal value.

20 25 30 35 40 45 50 55 60 65 66 With such a configuration, also in the present embodiment, the expansion coefficient E is obtained in the same manner as in the above first embodiment.

<3.2 Effect>

According to the present embodiment, the field-sequential color system is adopted for the driving system of the liquid crystal display device. By using the field-sequential color system, the color filters are not required, thereby making the light use efficiency high as compares with that of the liquid crystal display device employing the color filter system. This enables an increase in luminance and reduction in power consumption. From the above, there is achieved a liquid crystal display device capable of expanding a color space without causing increases in IC size and cost, and also capable of increasing luminance and reducing power consumption.

<3.3 Variant>

Also in a case in which the field-sequential color system is adopted for the driving system as in the above third embodiment, the expansion coefficient E may be obtained in the same manner as the above second embodiment. That is, in the liquid crystal display device employing the field-sequential color system, the average (or the median) of the "inverses of saturation" for the plurality of pixels (the target pixel and the pixels therearound) may be decided as the expansion coefficient E for the target pixel.

According to the present variant, it is possible to exert the effects which are obtained in the above first to third embodiments. That is, there is achieved a liquid crystal display device capable of expanding a color space without causing increases in IC size and cost, capable of obtaining a display image with smooth color variation, and capable of increasing luminance and reducing power consumption.

4. Others

The present invention is not limited to each of the above embodiments. A variety of modification may be made so long as not deviating from the scope of the present invention. For example, although the description has been made by using the example where one frame period is temporally divided into four fields in the above third embodiment, the present invention is also applicable to a liquid crystal display device adopting a field-sequential color system in which one frame period is divided into five or more fields. Further, the present invention is also applicable to a display device other than the liquid crystal display device.

DESCRIPTION OF REFERENCE CHARACTERS

100: SIGNAL PROCESSING CIRCUIT

110: SIGNAL SEPARATION UNIT

120: EXPANSION COEFFICIENT DECISION UNIT

130: EXPANDED VIDEO SIGNAL GENERATION UNIT

140: OUTPUT VIDEO SIGNAL GENERATION UNIT

200: TIMING CONTROLLER

310: GATE DRIVER

320: SOURCE DRIVER

330: LED DRIVER

400: LIQUID CRYSTAL PANEL

410: DISPLAY UNIT

500: BACKLIGHT

E: EXPANSION COEFFICIENT

DIN: INPUT VIDEO SIGNAL

Ri, Gi, Bi: RED INPUT VIDEO SIGNAL, GREEN INPUT VIDEO SIGNAL, BLUE INPUT VIDEO SIGNAL

Re, Ge, Be: RED EXPANDED VIDEO SIGNAL, GREEN EXPANDED VIDEO SIGNAL, BLUE EXPANDED VIDEO SIGNAL

Wo, Ro, Go, Bo: WHITE OUTPUT VIDEO SIGNAL, RED OUTPUT VIDEO SIGNAL, GREEN OUTPUT VIDEO SIGNAL, BLUE OUTPUT VIDEO SIGNAL

The invention claimed is:

1. A display device provided with a display panel for displaying an image, the display device comprising:

a processor;

an expanded video signal generation circuit configured to perform an expansion process for increasing a signal value of an input video signal, and output data obtained by the expansion process as an expanded video signal; an expansion coefficient decision circuit configured to decide an expansion coefficient to be used for the expansion process by the expanded video signal generation circuit; and

an output video signal generation circuit configured to generate an output video signal to be outputted to the display panel based on the expanded video signal, wherein

the expansion coefficient decision circuit decides an inverse of saturation, obtained based on the input video signal, as an expansion coefficient for each pixel, the expanded video signal generation circuit multiplies the expansion coefficient, decided by the expansion coefficient decision circuit, by a signal value of the input video signal for each pixel, to generate the expanded video signal, and

when a pixel to be processed for obtaining the expansion coefficient is defined as a target pixel, the expansion coefficient decision circuit decides an expansion coefficient to be used for the expansion process on an input video signal of the target pixel based on input video signals of a plurality of pixels included in a predetermined range centered on the target pixel.

2. The display device according to claim 1, wherein the expansion coefficient decision circuit decides an average of inverses of saturation, obtained based on input video signals of the plurality of pixels, as an expansion coefficient to be used for the expansion process on an input video signal of the target pixel.

3. The display device according to claim 1, wherein the expansion coefficient decision circuit decides a median of inverses of saturation, obtained based on input video signals of the plurality of pixels, as an expansion coefficient to be used for the expansion process on an input video signal of the target pixel.

4. The display device according to claim 1, wherein the input video signal includes a red input video signal, a green input video signal, and a blue input video signal, the display panel is configured to display an image based on the output video signal including a white output video signal, a red output video signal, a green output video signal, and a blue output video signal, the expanded video signal generation circuit:

generates a red expanded video signal based on the red input video signal;

generates a green expanded video signal based on the green input video signal; and

generates a blue expanded video signal based on the blue input video signal,

the output video signal generation circuit:

generates the white output video signal based on the red expanded video signal, the green expanded video signal, and the blue expanded video signal;

17

generates the red output video signal based on the white output video signal and the red expanded video signal;
 generates the green output video signal based on the white output video signal and the green expanded video signal; and
 generates the blue output video signal based on the white output video signal and the blue expanded video signal.

5. The display device according to claim 4, wherein one pixel includes a white sub pixel that displays white, a red sub pixel that displays red, a green sub pixel that displays green, and a blue sub pixel that displays blue, the white output video signal is provided to the white sub pixel,
 the red output video signal is provided to the red sub pixel, the green output video signal is provided to the green sub pixel, and
 the blue output video signal is provided to the blue sub pixel.

6. The display device according to claim 4, wherein the display panel is driven by a field-sequential color system in which one frame period is divided into a plurality of fields and a screen is rewritten in each of the fields to produce a color display,
 one frame period includes a white field for displaying a white screen, a red field for displaying a red screen, a green field for displaying a green screen, and a blue field for displaying a blue screen,
 the white output video signal is outputted to the display panel in the white field,
 the red output video signal is outputted to the display panel in the red field,

10

15

20

25

30

18

the green output video signal is outputted to the display panel in the green field, and
 the blue output video signal is outputted to the display panel in the blue field.

7. A method for expanding a color space in a display device provided with a display panel for displaying an image, the method comprising:
 an expanded video signal generation step of performing an expansion process for increasing a signal value of an input video signal, and outputting data obtained by the expansion process as an expanded video signal;
 an expansion coefficient decision step of deciding an expansion coefficient that is used for the expansion process in the expanded video signal generation step;
 an output video signal generation step of generating an output video signal to be outputted to the display panel based on the expanded video signal, wherein
 in the expansion coefficient decision step, an inverse of saturation, obtained based on the input video signal, is decided as an expansion coefficient for each pixel,
 in the expanded video signal generation step, the expansion coefficient decided in the expansion coefficient decision step is multiplied by a signal value of the input video signal for each pixel, to generate the expanded video signal, and
 when a pixel to be processed for obtaining the expansion coefficient is defined as a target pixel, the expansion coefficient decision step decides an expansion coefficient to be used for the expansion process on an input video signal of the target pixel based on input video signals of a plurality of pixels included in a predetermined range centered on the target pixel.
